UNITED STATES PATENT OFFICE.

HENRY F. HOWELL, OF DIVIDE, WEST VIRGINIA.

RATCHET DRILL.

1,403,603.

Specification of Letters Patent. Patented Jan. 17, 1922.

Application filed January 15, 1921. Serial No. 437,590.

To all whom it may concern:

Be it known that I, HENRY F. HOWELL, a citizen of the United States, residing at Di-

5 vide, in the county of Fayette and State of West Virginia, have invented certain new and useful Improvements in Ratchet Drills, of which the following is a specification, reference being had to the accompanying drawings.

10 This invention relates to certain improvements in ratchet drills, and it is an object of the invention to provide a novel and improved device of this character including a tool carrying shank in threaded engagement 15 with a working barrel and with which is associated an operating lever adapted to be reversely swung or rocked, together with co-acting means carried by the shank and lever whereby the shank may be rotated upon 20 swinging movement of the lever in both directions.

Another object of the invention is to provide a device of this general character with novel and improved means whereby the extent 25 of rotation of the tool carrying shank upon rocking or swinging movement of the operating lever may be regulated or varied or whereby the lever may be rendered inoperative upon movement in one direction.

30 The invention consists in the details of construction and in the combination and arrangement of the several parts of my improved ratchet drill whereby certain important advantages are attained and the device 35 rendered simpler, less expensive and otherwise more convenient and advantageous for use, as will be hereinafter more fully set forth.

The novel features of my invention will 40 hereinafter be definitely claimed.

In order that my invention may be the better understood, I will now proceed to describe the same with reference to the accompanying drawings, wherein:

45 Figure 1 is a view partly in elevation and partly in section of a ratchet drill constructed in accordance with an embodiment of my invention.

Figure 2 is a view partly in end elevation 50 and partly in section of the device as illustrated in Figure 1.

Figure 3 is a sectional view taken substantially on the line 3—3 of Figure 1.

Figure 4 is a view in top plan of the de- 55 vice as herein embodied.

Figure 5 is a view in elevation of the plate

herein included and upon which is pivotally mounted a lever for operating one of the pawls.

Figure 6 is a view in elevation of the arm 60 or strap coacting with the pivoted lever as particularly illustrated in Figure 5 for imparting swinging movement to said lever, and

Figure 7 is a sectional view taken substantially on the line 7—7 of Figure 4.

As disclosed in the accompanying drawings, 1 denotes an elongated working barrel open at one end and closed at the opposite end, the closed end portion being provided with the taper or point 2 for a well known purpose. The open end portion of the barrel 1 is provided with an internal nut 3 having in threaded engagement therewith the elongated shank 4, said shank extending 75 inwardly of the barrel 1.

The outer end portion of the shank 4 is provided with an enlargement or head 5 provided in its outer face with a socket 6 to receive the boring tool or bit. The shank 4 80 extends inwardly of the head 5 but in close proximity thereto has fixed thereon a ratchet wheel 7 and loosely or freely engaged with the shank 4 at opposite sides of the ratchet wheel 7 are straps or arms 8 and 9, the strap 85 or arm 8 being arranged between the head 5 and the ratchet wheel 7 and the strap or arm 9 being arranged inwardly of the ratchet wheel 7.

The straps 8 and 9 overlie the side faces 90 of an operating lever L of desired length and are suitably secured thereto. Pivots supported between the straps or arm 8 and 9 is a pawl 10. The pawl 10 coacts in a conventional manner with the ratchet wheel 7 95 and upon swinging or rocking movement of the lever L in one direction, said pawl 10 engages the ratchet wheel 7 to effect rotation of the shank 4 in a direction to cause said shank to travel or move outwardly with 100 respect to the barrel 1.

The shank 4 extends through an end portion of an elongated plate 11, said plate being positioned in close proximity to the strap or arm 9. Disposed through the shank 105 4 inwardly of the plate 11 is a key 12 coacting with the plate 11 in a manner whereby said plate is caused to move outwardly with the shank 4. Upon inward movement of the shank 4, the strap or arm 9 contacts 110 with said plate 11 to cause the same to move inwardly with the shank 4.

Suitably secured to the plate 11 at a desired distance outwardly from the shank 4 and the barrel 1 and at transversely spaced points are the similar end portions of the parallel rods 14. The rods 14 extend inwardly of the barrel 1 in parallelism therewith and the end portions of said rods remote from the plate 11 are secured to the plate 15 slidably mounted upon the barrel 1.

10 Mounted upon the end portion of the barrel 1 adjacent the open end thereof is a sleeve 16 which is adapted to be locked to the barrel 1 by the binding screws 17. The sleeve 16 is provided with an outstanding plate 18 disposed in the same direction as the plate 11 and through which the rods 14 are slidably disposed. The rods 14 operate to hold the plate 11 against lateral movement independently of the shank 4.

20 The end portion of the strap or arm 9 mounted upon the shank 4 is provided with an outwardly directed tail-piece 19. The tail-piece 19 carries a laterally directed part 20 which rides within the slot 21 extending lengthwise of the lever 22. The lever 22 is pivotally supported at 23 by the plate 11 and the pivoted end portion of the lever 22 is continued by the laterally directed extension 24. The outer or free end portion of the extension 24 is provided with a lug 25 extending outwardly therefrom in a direction lengthwise of the barrel 1.

30 Pivotedly engaged with the lug 25 is an end portion of an elongated pawl 26 adapted to engage the ratchet wheel 7 upon movement of the lever L in one direction or when the lever L is moving in a direction to return the pawl 10. The pawl 26 is freely disposed through a tubular member or barrel 27 carried by an end portion of an arcuate plate 28. The opposite end portion of the plate 28 overlies a forwardly or outwardly disposed extension 29 carried by the outer end portion of the plate 11.

40 The portion of the plate 28 which overlies the extension 29 is provided with a slot 30 through which extends the shank of a clamping bolt 31 in threaded engagement with the extension 29. The clamping bolt 31 in connection with the slot 30 provides means whereby the tubular member or sleeve 27 may be adjusted with respect to the ratchet wheel 7 to regulate the extent of rotation of the ratchet wheel 7 through the 50 instrumentality of the pawl 26 or to hold said pawl in a position at all times free of the ratchet wheel 7. When the tubular member or sleeve 27 is in this last named position, the shank 4 will only be rotated upon movement of the lever L in one direction and as effected by the pawl 10.

55 My ratchet drill is particularly adapted for use in the boring of rock, slate, coal and the like, and after the drilling or boring operation has been completed, the tool may

be readily and conveniently withdrawn by releasing the screws 17 from binding action upon the barrel 1 so that said barrel 1 may be freely rotated in a direction to cause the shank 4 to move inwardly of the barrel 1. 70

In order to facilitate the desired functioning of the pawl 26, I provide the arcuate member 28 with the spring 32 coacting with the pawl 26 and constantly urging the same in a direction toward the ratchet wheel 7. 75 The pawl 10 also has coacting therewith a spring 33 for constantly urging the same toward the ratchet wheel 7 and whereby the desired action of the pawl 10 is assured irrespective of the position of the device in its 80 entirety.

85 From the foregoing description it is thought to be obvious that a ratchet drill constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed. 95

I claim:

1. A device of the character described comprising two members in threaded engagement one with the other, a ratchet wheel 100 fixed to one of said members, a lever engaged with said member for swinging movement, a pawl carried by said member for coaction with the ratchet wheel to rotate said member upon movement of the lever in one direction, a plate carried by said member, a lever pivoted to said plate, both of said levers being provided with coacting means whereby said levers swing in unison, and a pawl carried by the second named lever and coacting with 110 the ratchet wheel, said second named pawl engaging the ratchet wheel to rotate the member upon movement of the first named lever to return the pawl carried thereby.

115 2. A device of the character described comprising two members in threaded engagement one with the other, a ratchet wheel fixed to one of said members, a lever engaged with said member for swinging movement, a pawl carried by said member for coaction 120 with the ratchet wheel to rotate said member upon movement of the lever in one direction, a plate carried by said member, a lever pivoted to said plate, both of said levers being provided with coacting means whereby said levers swing in unison, a pawl carried by the second named lever and coacting with the ratchet wheel, said second named pawl engaging the ratchet wheel to rotate the member upon movement of the first 125 130

named lever to return the pawl carried thereby, and means carried by the plate for adjusting the second named pawl with respect to the ratchet wheel.

5 3. A device of the character described comprising two members in threaded engagement one with the other, a ratchet wheel fixed to one of said members, a lever engaged with said member for swinging movement, a pawl carried by said member for coaction with the ratchet wheel to rotate said member upon movement of the lever in one direction, a plate carried by said member, a lever pivoted to said plate, both of said levers being provided with coacting means whereby said levers swing in unison, a pawl carried by the second named lever and coacting with the ratchet wheel, said second named pawl engaging the ratchet wheel to rotate the member upon movement of the first named lever to return the pawl carried thereby, a second plate adjustably connected with the first named plate, said second named plate being provided with a sleeve through which the second named pawl is freely directed, 70 said second named plate being arcuate, and provided with a longitudinally disposed slot, the first named plate being provided with an angular extension, the arcuate plate overlying said extension, and a member carried by the extension of the first named plate and extending through the slot of the arcuate plate for locking the arcuate plate in its different adjustments.

4. A device of the character described comprising two members in threaded engagement one with the other, a ratchet wheel fixed to one of said members, a lever engaged with said member for swinging movement, a pawl carried by said member for coaction with the ratchet wheel to rotate said member upon movement of the lever in one direction, a plate carried by said member, a lever pivoted to said plate, both of said levers being provided with coacting means whereby said levers swing in unison, a pawl carried by the second named lever and coacting with the ratchet wheel, said second named pawl engaging the ratchet wheel to rotate the member upon movement of the first named lever to return the pawl carried thereby, and a second plate adjustably connected with the first named plate, said second named plate being provided with a sleeve through which the second named pawl is freely directed, said second named plate being arcuate.

50 5. A device of the character described comprising two members in threaded engagement one with the other, a ratchet wheel fixed to one of said members, a lever engaged

with said member for swinging movement, a pawl carried by said member for coaction with the ratchet wheel to rotate said member upon movement of the lever in one direction, a plate carried by said member, a lever pivoted to said plate, both of said levers being provided with coacting means whereby said levers swing in unison, a pawl carried by the second named lever and coacting with the ratchet wheel, said second named pawl engaging the ratchet wheel to rotate the member upon movement of the first named lever to return the pawl carried thereby, a second plate adjustably connected with the first named plate, said second named plate being provided with a sleeve through which the second named pawl is freely directed, 70 said second named plate being arcuate, and provided with a longitudinally disposed slot, the first named plate being provided with an angular extension, the arcuate plate overlying said extension, and a member carried by the extension of the first named plate and extending through the slot of the arcuate plate for locking the arcuate plate in its different adjustments.

6. A device of the character described comprising two members in threaded engagement one with the other, a ratchet wheel fixed to one of said members, a lever engaged with said member for swinging movement, a pawl carried by said member for coaction with the ratchet wheel to rotate said member upon movement of the lever in one direction, a plate carried by said member, a lever pivoted to said plate, both of said levers being provided with coacting means whereby said levers swing in unison, a pawl carried by the second named lever and coacting with the ratchet wheel, said second named pawl engaging the ratchet wheel to rotate the member upon movement of the first named lever to return the pawl carried thereby, two plates mounted upon the barrel, one of said plates being slidable therealong, means for locking the second plate to the barrel, and a rod secured to the first named plate and the 100 slidable plate, said rod being slidably disposed through the last named plate.

In testimony whereof I hereunto affix my signature.

HENRY F. HOWELL.
